UNITED STATES PATENT OFFICE.

FRANK A. FREEMAN, OF OVERTON, PENNSYLVANIA, ASSIGNOR TO PIONEER SUSPENDER COMPANY, A CORPORATION OF PENNSYLVANIA.

GARTER-PACKAGE.

1,082,265.

Specification of Letters Patent.

Patented Dec. 23, 1913.

Application filed March 24, 1911. Serial No. 616,614.

To all whom it may concern:

Be it known that I, FRANK A. FREEMAN, a citizen of the United States, residing at Overbrook, in the county of Philadelphia, 5 State of Pennsylvania, have invented a new and useful Garter-Package, of which the following is a specification.

My invention relates to packaging pad garters.

10 The object is to provide a neat and stable package peculiarly adapted for display purposes and capable of being packed in a box of minimum depth.

15 Referring to the drawings:—Figure 1 is a plan view of a pair of pad garters placed upon and secured to a flat card in accordance with my invention and ready for insertion in the box. Fig. 2 is a section on line 2—2 of Fig. 1. Fig. 3 is a section on line 20 3—3 of Fig. 1.

Similar numerals refer to similar parts throughout the several views.

The garters each comprise a flat triangular nonelastic pad 4, a hook-member 5 secured to one of the upper corners of the pad, and a leg band 6, usually of elastic webbing, secured to the opposite corner of the pad and provided at its free end with means for engaging hook-member 5. Clasps or 25 hose-grips 7 for engaging the stockings are secured to the lower ends of the pads. The garters when properly folded and assembled in the manner to be described, are placed upon the square card 8, being held in place 30 thereon by band 9.

To form the package shown in the drawings, each leg band 6 is first folded beneath the upper extension of its respective pad 4. The garters are then placed, one upon 40 the other, with the folded leg bands and the upper extensions of the pads upon opposite edges of card 8, with clasps 7 extending in opposite directions. In this position the lower extensions of the pads lie 45 one upon the other without interposed webbing either between or beneath them, one of the clasps being preferably inserted be-

tween the leg band and the pad. In which position, button or projection 10 of the clasp engages the upper edge of the upper pad. 50 Band 9, passing around card 8 or secured thereto, passes across the narrowed lower extensions of pads 4, holding them securely upon the card. In this position of the parts, independent outward movement of 55 either garter is prevented by the engagement of button 10 with the upper edge of the upper pad, while retaining band 9 prevents the accidental slipping of the garters from the pads in other directions. 60

It will thus be seen that by my invention I am enabled to provide an extremely simple, stable and efficient packet. It is also to be noted that, as the retaining band merely passes across the lower narrowed 65 extensions of the pads, it does not interfere with the inspection of the upper pad, and that, as the leg bands are folded upon opposite sides of the card away from the superposed portions of the pads, the package will be flat and capable of packing 70 without springing in a shallow box. This band also serves as a convenient means for displaying words or devices indicating some quality, characteristic or the origin of the 75 garters.

What I claim is:—

A package comprising a substantially square card, a pair of pad garters, each having the leg band folded back of the pad, 80 the garters so assembled that the clasp end of one pad superimposes the clasp end of the other, the button of one clasp projecting approximate the curved top of the other pad, the said curved tops of the pads lying 85 along the opposite parallel margins of the card, and a retaining band secured around the card and garters midway said opposite parallel margins.

FRANK A. FREEMAN.
